UNITED STATES PATENT OFFICE.

GRACIA V. WOOD, OF WASHINGTON, DISTRICT OF COLUMBIA.

BRASSIERE.

Application filed August 6, 1925. Serial No. 48,615.

To all whom it may concern:

Be it known that I, GRACIA V. Wood, a citizen of the United States, residing in the city of Washington and District of Columbia, have invented certain new and useful Improvements in a Brassière, of which the following is a specification.

This invention relates to a brassière, more particularly to that type serving as breast lifters, and is designed primarily for use of women before reaching maturity, and the invention has for its object to provide, in a manner as hereinafter set forth, a garment of such class to prevent the dropping 10 of the breasts or protuberant glands thereby maintaining the same in normal or natural position to provide a symmetrical figure and impart grace to the form of the wearer and without causing any discomfort during the 15 wearing of the garment.

Further objects of the invention are to provide, in a manner as hereinafter set forth, a brassière of the type referred to, which is simple in its construction and arrangement, strong, durable, elastic, thoroughly efficient in its use for the purpose as aforesaid, readily arranged in position with respect to the bosom, capable of being worn without any inconvenient feeling to the 30 wearer, and inexpensive to manufacture.

With the foregoing and other objects in view, the invention consists of the novel construction, combination and arrangement of parts, as hereinafter more specifically described and illustrated in the accompanying drawings wherein is shown a brassière in accordance with this invention, but it is to be understood that changes, variations and modifications can be resorted to which fall 40 within the scope of the claim hereunto appended.

In the drawings wherein like reference characters denote corresponding parts through the several views:

45 Figure 1, is a front elevation of a brassière, in accordance with this invention, as applied to the wearer.

Figure 2, is a front elevation of the brassière, when extended.

50 Figure 3 is a fragmentary view, in front elevation, of a modified form.

A brassière in accordance with this invention comprises a body encircling band provided with a pair of spaced pockets, each shaped to conform to the contour of the breasts or protuberant glands, and a pair of

suspension members having their ends anchored with the band.

The body encircling band consists of front and a pair of combined side and back 60 portions and these latter are adapted to be detachably connected together for securing the band in encircling position with respect to the body of the wearer. The front comprises a bottom strip 1, which consists of 65 elastic webbing or reticulated elastic fabric, or any other suitable elastic material. The strip 1 is of substantial width and length, in fact the length of the strip 1 corresponds to the length of the entire front. The top 70 of the strip 1, between its vertical median and each end is provided with a semi-circular cutaway portion of the desired depth, and said portions are indicated at 2, 3. Secured to the top edge of the strip 1, centrally thereof is a short piece of fabric 4 which is arranged in spaced relation with respect to a pair of oppositely disposed tapered extension 5, 6, projecting from the inner ends of the combined sides and back 80 portions. The lower edges of the extensions 5, 6 are secured to the top edge of the strip 1, and each of said extensions gradually decrease in width from its inner end towards its point of joinder with a combined side 85 and back portion. The extensions 5, 6 at their inner ends are flush with the outer sides of the edges of the cutaway portions 2, 3 respectively and form continuations of such edges. The piece 4 has its ends flush 90 with the inner sides of the edges of the cutaway portions 2, 3 respectively and form continuations of such edges. The top edge of the piece 4 is of concave curvature.

By the foregoing construction the front 95 is set up with an elastic lower portion, a flexible non-elastic upper portion, and a pair of substantially semi-circular cut-out portions extending entirely through the non-elastic upper portion and partially 100 through the elastic lower portion of the front.

One of the combined side and back portions is indicated generally at 7 and the other at 8, and the former is of less length 105 than the latter. The portion 7 is formed from a strip 9 of non-elastic fabric provided at its outer end with a plurality of superposed hooks 10. The strip 9 has a straight lower edge which aligns with the lower 110 edge of the strip 1. The top edge of the strip 9 inclines upwardly from its outer to-

wards its inner end and terminates in the top edge of the extension 5. The inner end of the strip 9 is of materially greater width than the strip 1 and from the upper portion of such end projects the extension 5. The strip 1 has one end thereof secured to the edge of the strip 9 at the inner end of the latter below the extension 5.

The portion 8 comprising a strip 11 of non-elastic fabric which has a straight lower edge aligning with the lower edge of the strip 1. The top edge of the strip 11 inclines upwardly from its outer towards its inner end and terminates in the top edge of the extension 6. The inner end of the strip 11 is of materially greater width than the strip 1, and from the upper portion of such end projects the extension 6. The strip 1 has its other end secured to the edge of the strip 11 at the inner end thereof. An elastic piece of fabric 11' is secured to the outer end of the strip 11, and is provided with eyes 11'' to receive the hooks 10 for connecting the band in position.

Secured to the edge throughout of each of semi-circular cut-out portion is a pocket forming element of any suitable fabric material and of a shape to enclose the breast or protuberant gland. The said element functions to prevent the breast from dropping and thereby maintains the same in normal or natural position to provide, in connection with the body encircling band, a symmetrical figure and impart grace to the form of the wearer. One of said elements is generally referred to at 12 and the other at 13. Each of said elements is formed of an upper and a lower section 14, 15 respectively. The lower section is formed from a strip of fabric cut to provide a semi-circular lower edge and a semi-oval upper edge. The end terminal portions of said lower section are of less width than the intermediate portion thereof. The lower edge of the section 15 is secured throughout to the edge of a semi-circular cut-away portion. The end edges of the sections 15 are in alignment with the top edges of the piece of fabric 4 and extensions 5, 6, and further extend inwardly at right angles with respect to said piece 4 and extensions 5, 6. The section 14 is substantially of semi-oval contour and has its curved edge secured throughout to the upper edge of the section 15 and the top edge of the section 14 is in alignment with the end or top edges of the top section 15. By constructing each pocket forming element of the sections 14, 15 in the manner as referred to and the securing of a section 15 to the edge of a cut-out portion, a pocket of the desired contour and area is provided to receive and enclose the breast. The mouth of each pocket opens at the inner side of the band. The pocket forming elements 12 and 13 project forwardly from the front

of the band and in connection with a means to be hereinafter referred to will prevent the breast from dropping.

A binder or finishing tape 16 is arranged at the top edge of the band and elements 12, 13. This tape 16 may, if desired, be loosely enclosed within a binder strip, except at the ends thereof whereby adjustment upon the wearer may readily be made by sliding the binder strip upon the tape and then tacking the tape and binder strip together to insure an exact fit. A binder or finishing tape 17 is arranged at the end and top edges of the strip 1, and a binder or finishing strip 17' is arranged at the bottom edges of the strips 9 and 11.

Secured to the top edge of the strip 9, intermediate its ends, is one end of a supporting or shoulder strap 18, which has its other end secured to the inner side of the top of the pocket-forming element 12. Secured to the outer side of the top of the element 12 is one end of a supporting strap 19, and the other end of the latter is secured to the strap 18, intermediate its ends.

Secured to the top edges of the strip 11, intermediate its ends, is one end of a supporting or shoulder strap 20, which has its other end secured to the inner side of the top of the pocket-forming element 13. Secured to the outer side of the top of the element 13 is one end of a supporting strap 21, and the other end of the latter is connected to the strap 20, intermediate its ends.

The straps 18, 19, 20, and 21, provide means, in connection with the elements 12 and 13 to support the breasts in normal or natural position.

In the form shown in Figure 3 the front of the band is formed of an elastic lower portion 22 and a non-elastic upper portion 23. In this form the front is cut out to provide a pair of spaced openings, only one of which is shown, which is indicated at 24, and arranged partially in the upper and lower portions 22, 23 of the front. The opening extends above the longitudinal center of the front. A pocket-forming element 25 is secured throughout to the edge of the opening. The element 25 is constructed similar to the element 12 or 13. The supporting straps, only one shown, which is indicated at 26 has one end connected to the top edge of the front in alignment with the vertical median of the opening 24, and its other end connected to the top edge of a combined side and back portion 27. The upper portion 23 of the front is formed of one piece of material and terminates in the combined side and back portions.

It is thought that the many advantages of a brassière of the breast lifting type, in accordance with this invention can be readily understood, and although the preferred embodiments of the device is as illustrated

and described, yet it is to be understood that changes in the details of construction can be had which will fall within the scope of the invention as claimed.

5. What I claim is:

A brassière comprising a body encircling band having the lower part of the front thereof formed of a lengthwise extending elastic portion and the upper part of its 10 front non-elastic, said band further provided at its front with a pair of spaced cut-out portions extending through the non-elastic

part of said front and into the upper part of the elastic portion of said front, and a pocket forming element having its side and bottom edges secured to the edge bordering each cut-out portion and extended forwardly from said front, said pocket forming element having its mouth opening at the inner face of the front of the band and its top 15 edge secured throughout with the band.

In testimony whereof, I affix my signature hereto.

GRACIA V. WOOD.
